UNITED STATES PATENT OFFICE.

JOSEPH J. MAGRADY, OF CHICAGO, ILLINOIS.

PLATFORM-SCALE FOUNDATION.

Application filed May 20, 1922. Serial No. 562,374.

To all whom it may concern:

Be it known that I, JOSEPH J. MAGRADY, a citizen of the United States of America, residing at Chicago, in the county of Cook and State of Illinois, have invented certain new and useful Improvements in Platform-Scale Foundations, of which the following is a specification.

My present invention relates generally to platform scales, and more particularly to scale pits or foundations for the support of platform scales especially those operating substantially in the plane of the roadway surface, my object being the provision of an improved construction by which without materially increasing costs, I am able to do away with certain objections and disadvantages most frequently constituting the main cause of interference with the proper operation of the scale deck and at all times constituting a source of annoyance and expense.

It is a well known fact that in structures of the present character dirt and debris finding its way into the scale pits through and around the platform or scale deck, collects in the usual construction so rapidly as to necessitate frequent cleaning and quickly interfere with the proper operation of the scales more especially in view of the fact that owing to the usual difficulties in cleaning it is many times neglected.

My invention proposes a construction which at the same time provides for ready and easy cleaning of the pit and uniform effective support of the scale bearings, and consists in the construction and arrangement of parts shown in the accompanying drawing wherein

Figure 1 is a top plan view of my improved scale pit or foundation,

Figure 2 is a vertical section taken lengthwise thereof substantially on line 2—2 of Figure 1, and

Figures 3 and 4 are vertical transverse sections taken respectively on lines 3—3 and 4—4 of Figure 1.

Referring now to these figures my present invention proposes a scale pit or foundation which, as is usual, is of generally rectangular form, with upright side and end walls 10 and 11 respectively, one of the former of which has an entrance opening 12 at one side and a drain pipe 13 extending from the lower central portion of its opposite side.

Around the upper inner edges of the side walls 10 and 11, which are preferably formed of concrete or similar material, I preferably partially embed a protecting angle bar 14, the latter being held in place by anchor rods 15 embedded in the walls, so that the walls will thus have additional protection around the edges of the scale deck or platform which in its normal position is flush or substantially flush with the upper edges of the walls.

Centrally as well as at the four corners of the space within the walls 10 and 11 and terminating substantially below the upper edges of these walls, are a plurality of upright piers or pedestals 16 upon the upper ends of which are disposed bearing supporting plates 17, the latter being held with their surrounding edges extending slightly beyond the upper ends of the piers or pedestals, by means of anchor bolts depending into and embedded within the concrete or other similar material of which the piers or pedestals are formed. It will be noted by a comparison of Figures 1 and 2 that the bearing supporting piers or pedestals 16 are frusto-conical in form and each thereof is integral with and disposed upon a lower enlarged rectangular foundation block 18 and entirely independent of the base or floor 19 of the scale pit upwardly through which the piers or pedestals project whereby it becomes easier to set and level the piers in the first instance and cracks or breaks in the base of the scale pit cannot affect this setting.

The base or floor 19 of the scale pit inclines downwardly from the end walls 11 toward the center of the pit as will be clearly seen by reference to Figure 2, and as shown in Figures 3 and 4 it is also inclined transversely with its lowermost point adjacent to the inner end of the drain pipe 13, the latter of which may be connected in practice to a sewer or the like in order that the interior of the pit may be thoroughly drained at all times of water and dirt collecting within the pit.

It will also be observed by reference to the several figures that adjacent to the corners thereof and thus adjacent to the upright corner piers or pedestals, the lower adjoining portions of the side and end walls 10 and 11 are recessed or undercut in a downwardly and gradually deepening manner as indicated at 20 so that the walls of these recesses

parallel the adjacent portions of the side surface of the corner piers or pedestals, leaving ample and uniform spaces around these piers or pedestals at the corner of the 5 scale pit so as to avoid the ready collection and retention of dirt and debris at these points and permit of readily and easily washing out from the corners any such dirt and debris as may collect.

10 It is thus obvious that, owing to the independent setting and support of the several bearing supporting piers or pedestals, the floor or base of the scale pit may be suitably inclined in the manner described and formed 15 in place after the piers or pedestals have been disposed in proper positions and leveled and it is furthermore obvious that by slightly crowning the bearing supporting plate 17 at the upper ends of the several 20 bearing supporting piers or pedestals I avoid the collection and retention of dirt and debris which might fall upon the tops of the piers or pedestals and otherwise might interfere with proper operation of the scale parts supported thereby.

25 In view of the spaces around the corner piers or pedestals by virtue of recessing the side and end walls at their adjoining portions, and the inclining of the floor or base 30 of the pit it becomes an easy simple matter to flush out the dirt and debris by the use of a hose from time to time and at much more infrequent intervals than is necessary

to clean out the scale pits now proposed and in use. It is also obvious that by virtue of 35 the drain pipe extending as it does from the scale pit at the lowermost portion of the floor or base thereof, water and moisture is carried off at all times and, especially in freezing weather it is thus prevented from 40 interfering with the proper operation of the scales.

I claim:

1. A foundation or pit for platform scales having side and end walls and a base and 45 bearing supporting pedestals of frusto-conical form extending upwardly through the base at spaced points and having foundation supports below and independent of the base and rounded dirt shedding surfaces 50 above the base.

2. A foundation or pit for platform scales having side and end walls and a base and bearing supporting pedestals of frusto-conical form extending upwardly through the 55 base and having foundation supports below and independent of the base, certain of said piers or pedestals being located adjacent to the corners of the pit, and said side and end walls having downwardly deepening recesses 60 at their lower adjoining portions forming uniform curved spaces between the same and the corner piers or pedestals.

In testimony whereof I have affixed my signature.

JOSEPH J. MAGRADY.
